Patented Dec. 13, 1966

206,442

HOUSING FOR BATTERY OPERATED SOUND AMPLIFIER OR SIMILAR ELECTRICAL APPA- RATUS

Robert J. Mueller and Herbert L. Kornfeld, Los Angeles,
Calif., assignors to International Rectifier Corporation,
El Segundo, Calif., a corporation of California

Filed Apr. 30, 1965, Ser. No. 85,034

Term of patent 14 years

(Cl. D26—14)

FIGURE 1 is a front elevational view of a housing for a battery operated sound amplifier or similar electrical apparatus, showing our new design, the rear being substantially a mirror image thereof;

FIGURE 2 is a vertical cross-sectional view thereof, taken on line 2—2 in FIGURE 1, showing the innerposed platforms in the transparent upper cover;

FIGURE 3 is a top plan view;

FIGURE 4 is a bottom plan view; and

FIGURE 5 is an exploded perspective view thereof.

We claim:

The ornamental design for a housing for battery operated sound amplifier or similar electrical apparatus, as shown and described.
